UNITED STATES PATENT OFFICE.

NATHANIEL L. RIPLEY, OF BOSTON, MASSACHUSETTS.

DESIGN FOR A FINGER-RING.

SPECIFICATION forming part of Design No. 12,867, dated April 11, 1882.

Application filed March 2, 1882. Term of patent 3½ years.

To all whom it may concern:

Be it known that I, NATHANIEL L. RIPLEY, a citizen of the United States, residing at Boston, Suffolk county, State of Massachusetts, have invented and produced a new and original Design for Finger Rings, of which the following is a specification, reference being had to the accompanying drawing, forming part thereof.

The drawing shows in perspective a ring containing my design.

The ring herein shown as containing my design has its periphery beveled upward from its edge to its center, sunk transversely or across its width, forming diamond or lozenge shaped depressions *a* in intaglio, leaving along each edge of the ring, between the ends of the said depressions, triangular portions *b*. The diamond or lozenge shaped depressions are chased to present an ornamental border, *c*, and I preferably make a line of stipple-work, *d*, through the center of the lozenge-shaped depression from end to end.

I claim—

1. The design for finger-ring herein shown and described, it consisting of the transverse 25 depressed diamond or lozenge shaped figures and the intermediate figures, *b*, at each edge of the ring.

2. The design for finger-ring herein shown and described, it consisting of the transverse 30 diamond or lozenge shaped ornamenteally-bordered figures in intaglio and the intermediate triangular figures, *b*.

3. The design for finger-ring herein shown and described, it consisting of the transverse 35 diamond or lozenge shaped centrally-stippled figures *a* in intaglio and the intermediate triangular figures, *b*.

In testimony whereof I have signed my name to this specification in the presence of two subscribing witnesses.

NATHL. L. RIPLEY.
